APPARATUS FOR CLOSING BAGS

Robert N. Cundall, Lackawanna, and Lincoln A. Cundall, Buffalo, N. Y., assignors to Bagpak, Inc., New York, N. Y., a corporation of Delaware

Application July 15, 1933, Serial No. 680,538

12 Claims. (Cl. 112—11)

Our invention relates to a machine for closing the open ends of filled bags such as are used to contain granular or pulverulent materials, and more particularly bags made up of several plies 5 of paper or fabric.

One object of our invention is to devise a machine which will uniformly close filled bags, forming neat and efficient closures.

Our invention is particularly adapted to close 10 the ends of multi-ply paper bags by looping sewing thread over reinforcing cords, and adhering a strip of binding material over the ends of the plies and down the sides of the bag over the reinforcing cords and threads.

15 Certain features of the mechanism herein disclosed constitute improvements in, or modifications of, mechanism disclosed in the copending applications, Serial Number 640,758 of Robert N. Cundall, filed November 2, 1932 and Serial Number 666,114 of Robert N. Cundall and Lincoln A. Cundall, filed April 14, 1933. We also draw attention to the fact that certain of the features disclosed in the aforementioned applications and certain of the features disclosed in this application are likewise disclosed in the copending application, Serial Number 686,816 of Robert N. Cundall and Lincoln A. Cundall, filed September 9, 1933. These features for the most part comprise improvements in mechanism for applying 20 a strip of material over the end of the bag to thereby seal the same, and it is not our intention to herein claim those features which constitute elements of the inventions disclosed in the aforementioned applications.

25 Separate features of our invention which contribute to make it a practical machine will hereinafter be pointed out and will be apparent in the following specification taken in connection with the drawings, and particularly emphasized in the appended claims.

30 Referring to the drawings, wherein like numerals refer to like parts;

Fig. 1 is a front elevation of our entire machine;

Fig. 2 is an enlarged front elevation of a portion thereof;

Fig. 3 is an end elevation looking at the left end of Fig. 1;

Fig. 4 is a front elevation of the bag conveying carriage and a portion of the frame;

Fig. 5 is an end view thereof taken along the line 5—5 of Fig. 4;

Fig. 6 is an enlarged plan view of the bag grippers or clamps;

Fig. 7 is a front elevation thereof;

Fig. 8 is an end elevation thereof;
Fig. 9 is a cross section taken along the line 9—9 of Fig. 6;

Fig. 10 is a sectional elevation of the adhesive applying mechanism seen in Figs. 1 and 2;

Fig. 11 is a partial end elevation thereof;

Fig. 12 is a partial plan view thereof;

Fig. 13 is a view showing a guide roll over which the tape passes;

Fig. 14 is a perspective view of a tape guide associated with the guide roll;

Fig. 15 is a perspective view of the tape folder;

Fig. 16 is an end view thereof;

Fig. 17 is a plan view of the presser rolls and driving mechanism;

Fig. 18 is an end elevation thereof;

Fig. 19 is a plan view of the type of shears employed in my invention;

Fig. 20 is an elevation thereof; and

Fig. 21 is an exploded view in perspective of 20 the shears showing its component parts.

Our machine is shown in full in Fig. 1 and comprises four component parts which cooperate to stitch the bag, apply filler cords and binding tape thereto and press the tape firmly into place. The 25 component parts consist of a carriage indicated at A in Fig. 1, a sewing mechanism indicated at B, a tape gumming device indicated at C and a pressing mechanism indicated at D. Details of these parts and their inter-relationship will be 30 hereinafter pointed out with particularity in connection with the several views.

The frame of the machine consists of upright angle posts 10 and 11 joined by a reinforced angle beam 12 upon which parts of the machine 35 are mounted. Beam 12 is bolted to posts 10 and 11 through slots in their forward flanges, by means of which the machine may be adapted to close bags of varying heights by one simple adjustment of the beam on the posts.

Extending forwardly from the lower ends of posts 10 and 11 are angles 13 and 14 forming a base for the machine. Angles 15 and 16 extend forwardly from posts 10 and 11 above angles 13 and 14 and are bolted to the posts through 45 slots therein. The forward ends of angles 15 and 16 are supported by bars 17 having slots through which bolts adjustably attach the bars to the angles. Angles 15 and 16 may thus be adjusted at either end to level tracks 18 attached thereto, 50 or to bodily raise them to a different level. Tracks 18 extend beyond posts 10 and 11 and are braced by angles 19 joining their ends from which abutments 20 and 21 extend upwardly to limit the travel of the carriage on tracks 18.

55

Mounted on tracks 18 is the bag conveying carriage indicated at A in Fig. 1, and more fully detailed in Figs. 4 and 5. The floor frame 22 of the carriage is built up of angles from which 5 rise angle posts 23. A plate 24 is attached to posts 23 and curved outward over frame 22 and attached thereto. A second plate 25 is held forwardly of plate 24 by bolts 26 and is curved outward a short distance over plate 24. The curve 10 of plate 25 conforms to the shape of a filled bag as indicated in Fig. 5. Bolts 26 are adjustable to enable plate 25 to accommodate various sizes of bags while maintaining their centers in line with the closing mechanisms.

15 The carriage is supported on wheels 27 running on tracks 18. A cord 28 is attached to a pin 29 at the right end of the inner track 18 and passes under a pulley 30 attached to the carriage and over a pulley 31 (Fig. 1) mounted 20 on a post 32 extending upwardly from the left end of the track. A weight 33 is attached to the free end of cord 28. As the carriage is manually pushed toward the left, weight 32 is raised by the leveling of cord 28 under pulley 30. The 25 tension on cord 28, due to the weight 33, is calculated to return the carriage to the right against abutment 20 when empty, but will not be sufficient to move it when loaded with a filled bag.

30 The ends of carriage posts 23 are joined by an angle beam 35 above the upper edge of plate 24. Bars 36 are attached to beam 35 by means of bolts extending through slots which allow vertical adjustment of the bars. An angle beam 37 having one side extending forward over the carriage is 35 pivotally connected to the upper ends of bars 36. A spring 38 normally tends to keep bars 36 vertical, but allows their upper ends and beam 37 a limited movement toward the left.

40 Mounted on beam 37 are gripping jaws or clamps, indicated generally at 39 and 40 in Fig. 4, and detailed in Figs. 6, 7, 8 and 9. A description of one of the clamps will now be given, clamps 39 and 40 being identical, but opposed and in reversed relationship to grip the opposite edges of 45 a bag.

45 Plates 41 are bolted to the top of the forwardly extending side of beam 37 through slots which allow accommodation of different widths of bags. The inner jaw 42 is mounted on the end of a 50 plate 43 guided by flanged blocks 44 for sliding movement over the top of plate 41. A bolt 45 extending through a slot 46 in plate 41 and screwed into plate 43 assists in guiding the jaw and prevents any tendency to swing upward under pressure. A lug 47 on plate 43 extends downwardly through a slot 48 in plate 41 and carries a short rod 49. A spring 50 encircling rod 49 and compressed between lug 47 and a depending lug 51 on plate 41 tends to keep jaw 42 at its 55 outer position. Bolt 45 is shorter than the space between lugs 47 and 51 to allow the jaw inward movement. Jaw 42 is limited in its outward movement by an extension 52 of plate 43 which terminates in a curved surface bearing against 60 an opposed curved surface on the short arm 57 of pivoted jaw 53. Jaw 53 is pivotally mounted at 54 on plate 41 and has a finger hold 55 at its outer end. Extension 52 of plate 43 being outwardly of pivot 54 tends to keep jaw 53 against 65 jaw 42 under the compression of spring 50. A spring 59 stretched between a pin on plate 41 and a pin 56 on jaw 53 assures the closure of the pivoted jaw. Jaw 53 is free to swing inwardly against jaw 42, while the short arm 57 striking 70 plate 43 limits its outward movement. A short 75 plate 43 limits its outward movement.

channel bar 58 depending from the forward edge of plate 43 forms a convenient guide against which the operator can grip the side of a bag while positioning it. Jaws 42 and 53 are preferably cut away from each other inwardly from their ends and have inserted blocks which may be of some frictional material such as rubber, fiber or cork to insure a tight grip on the bag without marring its surface.

80 A guide 62 (Figs. 1, 4 and 5) is supported on an angle bar 60 extending horizontally to the right of post 11 and vertically adjustable thereon. Rods 61 extend forwardly from bar 60 and support the guide above the tops of the grippers 39 and 40. As seen in Fig. 4, the guide consists of a T-shaped bar 62 with the arms of the T vertical, rods 61 being adjustably attached through vertical slots in the upper arm. The leg of the T extends forward over the tops of jaws 42 and 53 for the greater part of its length 20 and is bent downward at its left end to form a constricted channel with the lower arm of the T, which channel is in line with the operating mechanisms B, C, and D.

The operator in positioning a filled bag places it upon the carriage while the carriage is at its extreme right position. By grasping the finger holds 55 on the movable gripping jaws and pulling them outward the jaws will be spread sufficiently to allow the insertion of the collapsed bag end. The operator holds one edge of the bag against the channel 58 of gripper 39, the mouth of the bag extending up through the open jaws against the lower vertical arm of the T-guide 62. Movable jaw 53 is now allowed to snap shut, the inner jaw 42 sliding inward against the compression of spring 51 to allow for the thickness of the bag, as shown in dotted lines in Fig. 6, while spring 59 holds the outer jaw 53 clamped against the outer side of the bag. The other edge of the bag is stretched taut and similarly clamped by gripper 40 as indicated in skeleton outline in Fig. 6. The operator can now move the carriage toward the left, the open projecting end of the bag being guided and compressed through the channel formed on guide 62.

85 As seen in Figs. 1, 3, 4 and 5, a plurality of operating treadles is mounted on rods extending between bars 13 and 14. Treadle 63 mounted at the right is so connected that it will draw a link 64 forward, rocking a shaft 65 and throwing an adjustable connecting rod 66 upward. Rods 66, Figs. 17 and 18, is pivotally connected to a bell crank 67, one arm of which forms a clutch yoke 68 straddling a shiftable clutch element 69 loosely mounted on a clutch shaft. A continuously rotating motor 70 is mounted on beam 12 and has a belt drive 71 to a pulley 72 formed on one flange of clutch element 69. A similar pulley 73 is mounted loosely on the clutch shaft, and a friction element is interposed between pulleys 72 and 73. The shifting of clutch yoke 68 and clutch element 69 forwardly by treadle 63 causes the motor 70 to drive the sewing unit B through pulley 13 and belt drive 14. The pulley 73 and sewing unit B normally tend to remain idle so that continued pressure on treadle 63 is necessary to operate the sewing unit and the releasing of pressure on the treadle will cause the sewing unit to stop.

90 A similar treadle 75 is so connected to shaft 65 as to pull connecting rod 66 downwardly and shift clutch element 69 toward the rear. A friction clutch element 76 formed on the other flange of clutch element 69 is forced against an opposed friction clutch element 77 fixed to the shaft. The

shaft extends out over the top of the tracks 18 and drives the tape pressing mechanism through a gear within a housing 78 and a worm gear affixed on the shaft.

5 By driving both the sewing mechanism and the pressing mechanism through a single shiftable clutch element operated by treadles 63 and 75, it is positively insured that only one of said mechanisms can be operated at one time. The 10 treadles are spaced so that the operator can depress only the appropriate treadle to operate the mechanism in which the bag is then positioned.

The operator, grasping the bag or a portion of 15 the carriage, causes the carriage to roll forward along tracks 18, while depressing treadle 63. The projecting open end of the bag is guided into the sewing mechanism B where it is stitched along a line parallel to its mouth, the stitching being 20 looped over cords formed of twisted strips of paper or other material, termed reenforcing cords, which prevent the sewing thread from tearing through the walls of the bag. The sewing unit B preferably of the type described and claimed in 25 Letters Patent of the United States #1,963,652 issued to Robert N. Cundall and dated June 19, 1934, is conveniently mounted on a bracket fastened to beam 12 and operates in a well-known manner, the sewing thread being supplied from 30 spools mounted on holders 81 and drawn through guides 82, while the filler cords are supplied from spools held in baskets 83 and drawn through guides 84. The bag end is gripped by the sewing machine feed-dog and fed forwardly in rapid, 35 jerky steps, spacing the needle holes approximately a quarter of an inch apart. The action of the feed dog is sufficient in itself to tend to feed the bag and carriage forward, but their combined inertia would cause the dog to slip. 40 and uneven stitching would result if it were not that the grippers 39 and 40 were allowed to oscillate slightly in the direction of travel due to their being mounted on the bars 36 biased by spring 48. The bag is completely stitched and 45 fed out to the left of the sewing unit B before the operator releases treadle 63.

The reinforcing cords are looped together by the sewing thread and trail behind the bag, attaching it to the sewing mechanism. Therefore 50 a shearing or clipping mechanism is mounted to the left of the sewing unit to separate the bag therefrom.

This clipping mechanism is indicated generally at 85 in Fig. 1 and detailed in Figs. 19, 20 and 21, 55 and will now be described. The mechanism is mounted on a bracket 86 supported on and above beam 12 and extends forwardly into the line of travel of the bag end. A fixed blade 87 is positioned behind and to one side of the bag and 60 a movable blade 88 swings inward from the forward side of the bag to cooperate therewith. The bracket 86 terminates in a machined bearing face 89 having a pivot hole 90 therein through which the pivot 91 of the movable blade 88 extends. Blade 87 is mounted on a boss 92 depending from bracket 86 and relieved inwardly from the bearing face 89. The blade is attached thereto by screws 93 countersunk into the blade and forms a continuation of bearing face 89. 65 Movable blade 88 is mounted on a pivoted block 94 having a hole 95 through which pivot pin 91 extends. The blade is attached by countersunk screws 96 and is backed against a guide 97 which extends forwardly from block 94 and bears 70 against face 89 of bracket 86. Pins 98 extend

through openings 99 in block 94 and terminate in smooth flat heads 100 which also bear against face 89. The heads 100 and the upper end of blade 88 form three points of contact guiding the movable blade when it is free from contact with the fixed blade. An operating lever 101 is pivoted on a boss 102 on bracket 86 and extends forwardly and upwardly therefrom terminating in a handle 103. A boss 104 at its inner end bears against boss 102 and a pivot pin 105 extends 10 through both. A short arm 106 depends from lever 101 and has a boss 107 extending inwardly from its lower end in which an elongate hole or slot 108 is formed. A bolt 109 extends through hole 108 and is fixed at its inner end in a hole 110 in block 94 by means of a set screw 111. The elongate hole 108 allows translation of the downward movement of handle 103 to the pivoting of movable blade 88. The pivot 91 of the movable blade extends through hole 95 and has a 20 reduced end 112 extending through hole 90 and fixed to the bracket by nut 113. A similarly reduced end 114 has a nut 115 thereon by means of which the compression of a spring 116 encircling the pivot pin and bearing against the outer face of block 94 may be adjusted to regulate the force with which the movable blade is pressed against the fixed blade. Spring 116 holds the movable blade in contact with the fixed blade, and pins 98 against surface 89, throughout the 30 movement of blade 88 so that the blades cut cleanly throughout the entire shearing stroke. Bracket 86 has a hole 117 therein in which a pin 118 is mounted. A spring 119 is stretched between pin 118 and the outer end of one of the 35 pins 98. Spring 119 opens the blades and lifts handle 103 to its normal position. An abutment for limiting the travel of the movable blade is provided by a cap screw 120 mounted in hole 121. Arms 122 and 123 of member 94 straddle the 40 screw head and thus the movement of blade 88 is limited in both directions of travel.

It is thus seen that a compact adjustable clipping mechanism is provided which will quickly clip the attached reinforcing cords and does 45 not require the attention of the operator to return it to inoperative position.

The leading edge of the bag mouth extends forwardly into a tape folding guide 125 when the trailing edge clears the clipping mechanism 85. 50 A strip of adhesive binding tape is folded by the guide or former 125 over the mouth of the bag and down along its sides, covering the reinforcing cords. The tape is supplied from a roll 126 (Fig. 1) and is gummed and folded over the bag 55 by mechanism indicated at C in Fig. 1 and detailed in Figs. 2, 3, and 10 to 16 inclusive.

The tape is preferably of crinkly kraft paper and is supplied from a roll 126 loosely mounted on a bracket 127 extending forward over the bag 60 from an angle post 128 mounted on beam 12. The tape extends downwardly into the gumming mechanism, detailed in Figs. 10, 11 and 12, wherein adhesive is applied to its lower surface by a roller 129 dipping into a bath of adhesive in a 65 tank 130. The tank is mounted on a rod 131 extending forward from angle post 128. A doctor blade 132 is attached to one end of the tank and extends across the surface of roll 129 and a short distance inwardly along each side. The clearance of the blade 132 may be adjusted by means of bolt 133 attaching it to the tank, the roll thereby being allowed to pick up sufficient adhesive to form a good union of the bag and tape, but not more than will require a limited time 75

to firmly set. Roll 129 is mounted on pivot pins 134 screwed into lugs extending upwardly from the side walls of tank 130 and fixed by set screws 135. As seen in Fig. 12, one or both of pivots 134 5 may have a knurled head by means of which it is easily adjusted. Screws 135 may also have knurled heads 136 to allow their ready adjustment. Screws 135 extend through bars 137 and have knurled lock nuts 138 thereon holding the 10 bars 137 firmly against the tops of the lugs in which pivots 134 are mounted. Bars 137 extend beyond the ends of tank 130 and carry a guide roll 139 at each end about which the tape is guided so that it is held against roll 129 for nearly 15 half of its periphery. Fixed to the ends of bars 137 on the side of the tank from which the gummed tape leaves, are cross bars 140 terminating in outward flanges 141 at their upper ends and forks 142 at their lower ends. A wiper blade 143 extends across the lower surface of the guide 20 roll 139 and is guided by the forks 142. Springs 144 attached to the ends of blade 143 and to the flanges 141 yieldingly press the blade upward against the gummed surface of the tape to wipe off any excess adhesive while spreading and 25 smoothing the adhesive on the tape. A drip plate 145 is attached to blade 143 and extends into the tank 130 to return any excess adhesive thereto.

The gummed tape as it leaves the adhesive 30 applicer is guided by a flanged plate 148 detailed in Fig. 14. This plate is supported by depending arms 149 through which the pivot of a disc roll extends. The tape is guided around this roll and has its gummed surface in contact therewith, so that in order not to remove the adhesive 35 from the tape, the roll is built up of discs 150 separated by spreaders 151. The roll is supported in arms 152 extending upwardly from a bracket 153 attached to the frame. The tape is then 40 guided forward over a flanged roll 154 the lower edge of which is positioned over the upper end of the bag. The tape, horizontally positioned above the end of the bag, is drawn forward into a former 125 (Fig. 15). The former is attached 45 to bracket 153 and consists of a curved plate which terminates in a flange 155 guiding the tape therein. The other end of the plate is bent almost upon itself as seen in 156, the transition from one end to the other being gradual and allowing the tape to bend over the sides of the bag 50 in a smooth, neat manner. The edges of the tape are guided in reentrant portions 157 extending along the edges of the plate. The leading edge of the bag is positioned within the former 125 and is stopped therein, before it contacts the gummed tape, while the operator clips the reinforcing cords by means of shears 85.

The operator now depresses treadle 75 causing the shifting of the clutch element 69 to the rear 60 and rotation of the gearing in housing 78. The tape pressing mechanism D is rotated through these gears and presses the tape firmly against the sides of the bag to insure a close adherence of the tape thereto while feeding the bag forward. The pressing mechanism is detailed in 65 Figs. 1, 2, 17 and 18 and will now be described.

A shaft extends downwardly from the housing 78 and is supported in a vertical bearing at the end of a bracket 160, which also supports the 70 clutch and associated pulleys. A sprocket 161, a gear 162 and a pressing and feeding roll 163 are fixed to this shaft and rotate therewith, the pressing roll being located to the rear of the upper edge of the bag. A similar shaft is mounted to the left of the first shaft on an extension of

bracket 160 and carries a similar sprocket 164, gear 165 and pressing roll 166. A third shaft is mounted to the right of the housing and carries a similar sprocket 167, gear 168 and pressing roll 169. A sprocket chain 170 is driven by 5 sprocket 161 and drives sprockets 164 and 167, rotating their associated gears and pressing rolls. An idler sprocket 171 bears against the sprocket chain and adjusts its tension by means of an adjustment screw 172 bearing against the arm on 10 which the idler is pivoted and an abutment fixed to bracket 160. Mounted forwardly of each of these three vertical shafts are similar shafts carrying gears meshing with the opposed gears and pressing rolls bearing against the opposed pressing rolls. Thus the gear 161 drives a gear 173 and a pressing roll 174, gear 164 drives a gear 175 and a pressing roll 176, and gear 167 drives a gear 177 and a pressing roll 178. These three outer shafts are resiliently pressed inwardly toward the inner shafts, the pressing roll 173 being mounted on arms 179 and the pressing roll 176 being mounted on opposed arms 180, the arms being pivoted to an extension of bracket 160. A lug 181 having a bolt 182 therein forms a bell crank with the arms 179, and a lug 183 having a bolt 184 therein forms an opposed bell crank with the arm 180. A spring 185 is seated on bolts 182 and 184 and resiliently forces the pressing rolls 174 and 176 against pressing rolls 163 and 166. The compression of spring 185 may be adjusted by means of a nut 186 on bolt 184. Gear 177 and roll 178 are mounted on arms 190 pivoted at 191 on an extension of bracket 160. A bolt 192 is threaded into this extension and passes 35 through an arm 193 integral with arms 190. A spring 194 bears against arm 193 and a nut 195 on bolt 192 by means of which its compression may be adjusted. It is thus seen that after the tape is applied to the mouth of the bag by the 40 former 125 it passes between three sets of rolls which not only feed the bag forward but resiliently press the tape firmly thereon, the pressure applied being easily regulated.

Each of the pressing rolls has a groove 196 45 extending around its periphery through which the bulge caused by the reinforcing cords may pass while allowing the surface of the roll above and below the groove to press firmly against the tape.

A set screw 197 is mounted in one of arms 190, the end of which bears against bracket 160 to limit the inward movement of roll 178. Set screw 197 is adjusted so that rolls 169 and 178 grip the mouth of the bag therebetween to feed it 55 forward, but will not grip and feed the tape alone.

Mounted on bracket 160 in the space between the first and second pressing rolls is a shearing mechanism 200 which is identical with the shearing mechanism 85 previously explained. As the 60 trailing edge of the bag reaches a position past the shears 200 the operator releases treadle 75 and operates the shears to clip the tape. The portion of the tape remaining between the first set of pressing rolls will be in position to be fed 65 forward with the next bag. Treadle 75 is now depressed to feed the bag through the second and third sets of presser rolls, whereupon it is removed from the carriage. While the operator is engaged in disposing of the closed bag, the carriage returns of its own accord to the right end of the tracks in position to receive another open bag.

It will now be apparent that we have devised a compact and efficient machine which will close 75

- the ends of filled bags in the manner described to form a neat, tight closure, with a minimum of time and effort being expended by the operator of the machine.
- 5 As will be evident to those skilled in the art, our invention permits of modifications in many of its component parts while not departing from the spirit thereof, and we do not intend to be limited to the specific details illustrated, the scope 10 of our invention being set forth in the following claims which are to be broadly construed.

What we claim is:

1. In a filled bag closing machine, means to convey a filled bag through the machine comprising a bag supporting and holding carriage, means to stitch through the open end of the bag, and means to apply a strip of adhesive tape over the stitched end, said conveying means being so constructed and arranged as to continuously engage 20 the end of the bag and maintain the same in a straight line of travel through said stitching and applying means.
2. In a filled bag closing machine, means to convey a filled bag through the machine, means to stitch through the open end of the bag, means to apply a strip of adhesive tape over the stitched end, and means to press the tape against the sides of the bag, said conveying means having grippers so mounted and constructed as to continuously engage the end of the bag and maintain the same in a straight line of travel during the presentation of the bag to each of said means and during the operation of each of said means upon the bag.
3. In a filled bag closing machine, a carriage to convey a filled bag therethrough, said carriage having bag end gripping jaws thereon mounted to oscillate in the direction of travel.
4. In a filled bag closing machine, a carriage to convey a filled bag therethrough, said carriage having bag end gripping jaws thereon mounted to oscillate in the direction of travel, and, means to cause the return of the carriage to its initial position when the bag is removed therefrom.
5. In a filled bag closing machine, a bag-conveying carriage, said carriage having a back wall adjustably mounted to accommodate different sizes of bags while maintaining their open ends in the same line of travel, said carriage also having opposed gripping jaws mounted thereon adjustable in two directions to adapt them to grip the open ends of bags of different heights and widths.
6. In a filled bag closing machine, bag closing means, a carriage having opposed gripping jaws thereon adapted to grip the open end of a filled bag and maintain it in line with said closing means, said jaws being held closed by resilient means allowing them to accommodate different thicknesses of bags.
7. In a filled bag closing machine, bag closing means, a carriage having opposed grippers thereon adapted to grip the open end of a filled bag and maintain it in line with said closing means, each of said grippers comprising an inner jaw guided for rectilinear movement on a supporting plate and resiliently forced outward, and an outer jaw pivoted on said supporting plate and resiliently forced inward.
8. In a filled bag closing machine, bag closing means, a carriage having opposed grippers thereon adapted to grip the open end of a filled bag and maintain it in line with said closing means, each of said grippers comprising an inner jaw guided for rectilinear movement on a supporting plate and resiliently forced outward, an outer jaw pivoted on said supporting plate and resiliently forced inward, and means to limit the movements of both jaws.
9. In a filled bag closing machine, bag closing means, a carriage having opposed grippers thereon adapted to grip the open end of a filled bag and maintain it in line with said closing means, each of said grippers comprising an inner jaw guided for rectilinear movement on a supporting plate and resiliently forced outward, an outer jaw pivoted on said supporting plate and resiliently forced inward, means to limit the movements of both jaws, and inserts of frictional material in the gripping surfaces of the jaws.
10. In a filled bag closing machine, a carriage having bag end grippers mounted to oscillate in the direction of travel of said carriage, a sewing machine beneath which said carriage travels and to which said grippers present the open end of the bag to be closed thereby, means to apply a tape to the end of the bag and covering the line of stitches to protect the stitches and seal the bag, a treadle controlling the operation of the sewing machine and a second treadle controlling the operation of the tape applying means, a rock shaft to which said treadles are connected on opposite sides so as to rotate the same in opposite directions, a clutch for said sewing machine and a second clutch for said tape applying means, a common clutch engaging lever causing engagement of either clutch upon movement in one direction and simultaneous disengagement of the other clutch, and a linkage connecting said clutch engaging lever to said rock shaft for movement in accordance with its direction of rotation so that neither the sewing machine nor the tape applying means may operate while the other of said means is in operation.
11. In a filled bag closing machine, means to stitch through the open end of a bag to close the same, means to apply a strip of adhesive tape over the end of the bag to protect the closing seam and prevent the escape of material, and a carriage to convey the main body of the bag through the machine in substantially uniform forward movement, said carriage being provided with bag end grippers so mounted as to allow the end of the bag to be stitched to progress in a series of intermittent movements through said stitching means in synchronism with the stitching action, and to progress in uniform movement through said tape applying means in synchronism with the main body of the bag.
12. In a filled bag closing machine, means to convey the main body of a filled bag through the machine in substantially uniform forward movement, and means to stitch through the open end of the bag, said conveying means comprising pivotally mounted grippers holding the end of the bag to be stitched and allowing said end to be progressed in a series of intermittent movements through said stitching means by the action of said stitching means.
